UNITED STATES PATENT OFFICE

BIRDORA H. WHITE, OF DETROIT, MICHIGAN

FASTENER

Application filed September 28, 1925. Serial No. 59,142.

The invention relates to fasteners such as are used for overall or suspender straps, or wherever a fastener for a pair of members is desired. One of the objects of my invention is to provide a simply constructed fastener which will not become accidentally disengaged but which will permit ready disengagement when desired. A further feature of my invention resides in the provision 10 of a fastener adapted to engage a button or a button hole.

With these and other objects in view, the invention resides in the novel features of construction and combination and arrangements of parts as more fully hereinafter described and claimed.

Referring to the drawings in which like reference characters indicate corresponding parts:

20 Figure 1 is a perspective view of my fastener;

Figure 2 is an elevation view of the same shown engaged with a button;

Figure 3 is a plan view thereof;

25 Figure 4 is a plan view showing the fastener engaged with a button hole;

Figure 5 is an elevation view along 5—5 of Figure 4;

30 Figure 6 is a perspective view of a modified type of fastener;

Figure 7 is an elevation view showing this modified type of fastener engaged with a button; and

35 Figure 8 is a view in elevation showing the fastener illustrated in Figure 6 in engagement with a button hole.

In the drawings, reference character 10 represents the fastener which may be formed of a resilient wire preferably bent to provide the elongated loop 11 and the loop 12, the latter preferably being of a clover leaf shape. These loops 11 and 12 extend parallel to each other in relatively offset planes and are connected by the neck 13. The loop 11 is adapted to engage one of two members to be connected together such as the overall strap 14^a, while the loop 12 is adapted to engage a button 14 secured to the other of the members to be connected together, as the cloth member 15. The width 16 of the clover

leaf loop is preferably slightly greater than the diameter of the button while the other dimension or length 17 of the clover leaf loop is preferably slightly less than the diameter of the button. Further the distance between 53 the portions A—A and B—B of loop 12 is slightly less than the diagonal thickness or radius of the button when the latter is tilted for engagement or disengagement with the loop, whereby even after the button is tilted, it must be forced between these portions, both of which yield slightly to permit passage of the button. By reason of the two loops being offset and the neck extending transversely therebetween, liability of disengagement 60 of the fastener from the button is avoided even if the length of the clover leaf loop is slightly greater than the diameter of the button.

As shown in Figures 4 and 5 the loop 12 of the fastener is equally well adapted for engagement with a button hole 18 in that it is provided with the portions 12^a and 12^b which extend at substantially right angles to the neck 13 or substantially parallel to the base 11^a of the loop 11, and the fact that the loop 12 is offset from the loop 11 assists in keeping the material 15 flat.

In Figure 6 the fastener 10' is formed substantially like the fastener 10 except that the loops 12' and 11' are not offset, these loops lying in the same plane. Figure 7 shows the loop 12' of this fastener engaging a button 14 and Figure 8 shows this loop 12' engaged in the button hole 18'.

While it is believed that from the foregoing description, the nature and advantage of my invention will be readily understood, I desire to have it understood, that I do not limit myself to what is herein shown and described and that such changes may be resorted to when desired as fall within the scope of the claims.

What I claim as my invention is:

1. A fastener comprising an elongated loop engageable with a strap and a second resilient loop integrally formed with the first said loop for engagement with a button, the dimensions of the second loop being so proportioned relative to the button that the second loop is en-

gageable with the button, only by a springing movement of the second loop.

2. A fastener comprising an elongated loop engageable with a strap and a second resilient loop integrally formed with the first said loop and engageable with a button, the dimensions of the second loop and button being such that engagement of the one with the other may only be effected by a springing movement of 10 the second loop, said loops being relatively offset.

3. A fastener comprising a resilient clover leaf shaped loop adapted for engagement with a button, the dimensions of the loop and 15 button being so proportioned that engagement of the one with the other may only be effected by a springing movement of the loop.

4. A fastener comprising a resilient clover leaf shaped loop adapted for engagement 20 with a button, one dimension of said loop being sufficient to freely receive the button, the said loop having portions spaced apart a distance slightly less than the diagonal thickness of the button whereby said portions must 25 be sprung to engage or disengage the button.

5. A fastener comprising a resilient clover leaf shaped loop adapted for engagement with a button, the length of the base of the loop being of sufficient dimension to freely 30 receive the button and the width of the base of the loop being of a dimension less than the diagonal thickness of the button whereby the loop must be sprung for engaging or disengaging the button.

35 6. A fastener comprising an elongated loop engageable with a strap, a second clover leaf shaped loop, and a connection between said loops, said cloverleaf shaped loop having portions extending at substantially right angles 40 to the said connection adapted for hooking engagement with the material adjacent a buttonhole.

7. A fastener comprising an elongated loop engageable with a strap, a second cloverleaf 45 shaped loop, and a connection between said loops, said cloverleaf shaped loop having a side parallel to one side of the said elongated loop to provide a portion adapted for hooking engagement with the material adjacent a buttonhole.

50 8. A fastener comprising an elongated loop engageable with a strap, a second clover leaf shaped loop, and a connection between said loops, said clover leaf shaped loop being 55 adapted for engagement with a button and also being provided with portions extending at substantially right angles to the said connection adapted for hooking engagement with the material adjacent a buttonhole.

60 9. A fastener comprising an elongated loop engageable with a strap, a second clover leaf shaped loop, said loops being arranged in parallel offset planes, and a connection between said loops, said clover leaf shaped loop 65 being adapted for engagement with a but-

ton, and being also provided with portions extending at substantially right angles to the said connection adapted for hooking engagement with the material adjacent a buttonhole.

In testimony whereof I affix my signature. 70
BIRDORA H. WHITE.
